UNITED STATES PATENT OFFICE.

LOUIS CALDWELL, OF EAST ORANGE, NEW JERSEY.

DESIGN FOR A BADGE.

No. 39,033.

Specification for Design.

Patented Jan. 28, 1908.

Application filed December 17, 1907. Serial No. 406,941. Term of patent 3½ years.

To all whom it may concern:

Be it known that I, LOUIS CALDWELL, a subject of the King of Great Britain, residing at East Orange, in the county of Essex and State of New Jersey, having invented a new, original, and ornamental Design for Badges, of which the following is a specification, reference being had to the accompanying drawing, forming part thereof.

The figure is a plan view of a badge, showing my new design.

I claim:

The ornamental design for a badge as shown.

LOUIS CALDWELL.
